HEAT TREATING FURNACE

Charles L. Peterson, Cicero, Ill., assignor to Western Electric Company, Incorporated, New York, N. Y., a corporation of New York

Application November 13, 1956, Serial No. 621,832

6 Claims. (Cl. 263—42)

This invention relates to heat treating apparatus and more particularly to an electric furnace for performing drying, baking, hardening, annealing, and tempering operations and other operations of a similar nature.

In the present invention, the disclosed apparatus is described as utilized to anneal spools of wire, but it will be manifest from the following description that the invention is equally applicable to various heat treatments of other types of work pieces.

In the manufacture of electrical conductors, large metal rods are generally drawn down to the desired wire size by means of wire drawing machines. When these wire drawing operations have been completed, the wire is in a "work hardened" state. Wire in this state does not have the ability to withstand repeated flexings without cracking which is generally required in electrical conductors. The wire must then be uniformly annealed to render it less brittle and hence suitable for use as an electrical conductor.

It is therefore a principal object of this invention to provide a heat treating apparatus which will heat work pieces uniformly throughout.

It is another object of this invention to provide a furnace which will rapidly and uniformly apply heated gases from a predetermined pattern of heating tubes to anneal spools of wire.

Another object of this invention is to provide a convection type annealing furnace in which the work being annealed does not project into the heating unit but is heated by a gas exiting from a plurality of uniformly spaced gas heating tubes.

With these and other objects in view, the present invention contemplates a convection type furnace including a heating chamber for containing work to be heat treated forming a part of a closed circuit for confining a gas and a convection blower for circulating the gas throughout the closed circuit. Heaters are provided for radiantly heating a portion of the closed circuit to impart heat to the circulating gas.

Other objects, advantages, and features of the invention will become apparent upon consideration of the following detailed description in conjunction with the accompanying drawings wherein:

Fig. 1 is an elevation view, in full section, of a heat treating furnace embodying the principal features of the invention;

Fig. 2 is a sectional view taken along the line 2—2 of Fig. 1 illustrating the arrangement of the gas heating tubes which provides uniform temperatures at all points in planes parallel to the base of the apparatus; and

Fig. 3 is a sectional view taken along the line 3—3 of Fig. 1 illustrating a plurality of spools of wire resting on the open grillwork which supports the work within the heating chamber.

Attention now is directed to the drawings wherein like numerals of reference designate like parts throughout the several views and wherein a base 11 is provided with a

2

convection blower 12. The base 11 is further provided with a plurality of posts 14 which support an apertured baffle plate 15 and work supporting grillwork 16 in spaced relationship above the base.

5 A work heating chamber, designated generally by the reference numeral 17, rests upon the base. This chamber comprises a metal inner baffle chamber 19 and an outer shell 20 of refractory material; both held in concentric relationship by a metal cover plate 21 to which they are secured. A metal sealing ring 22 depends from the lower extremity of the shell 20. This ring projects into a sealing liquid 24 within a sealing trough 25 fixed to the base 11 and thereby provides a gas tight seal. The outer shell 20 is further provided with hooks 26 or the like to permit attachment of any suitable means for raising and lowering the work heating chamber 17 to permit the furnace to be loaded and unloaded.

A plurality of return bend radiant heating tubes 27 are secured within apertures in the cover plate 21. First 20 extremities 29 of these tubes connect with a passage 30 created by the concentric relationship of the baffle chamber 19 and outer shell 20. The second extremities 31 of the tubes 27 open into the top of the baffle chamber 19 formed by the cover plate 21. Attention is particularly 25 directed to the uniform arrangement of the exit ends 31 of the tubes 27 into two concentric squares wherein there is equal spacing between the exit ends in each square.

A gas heating bell, designated generally by the reference numeral 32, rests atop the work heating chamber 17. The interior of the gas heating bell 32 is provided with a plurality of vertically depending radiant electric heating elements 34 which are energized by any suitable means. The gas heating bell is further provided with a hook 35 secured to the top thereof to which may be attached any suitable means for raising and lowering the bell.

Operation

In order that a better understanding of the invention 40 may be had, its mode of operation during a typical annealing process will now be described. The work to be annealed is first placed upon the open grillwork 16 in an orderly manner and uniformly distributed over the top of the grillwork. In the drawings, the work to be annealed 45 has been illustrated as spools of wire 36, which are resting upon the grillwork 16; only one layer of spools being shown for purposes of clarity. The work heating chamber 17 is then lowered to the position shown in Fig. 1. In this position, the sealing ring 22 is partially immersed 50 in the sealing liquid 24 and a gas tight seal is formed between the work heating chamber 17 and the base 11. Additionally, when the heating chamber 17 is in this position, a closed gas circuit is formed which is bounded by the 55 walls of outer refractory shell 20, the walls of the baffle chamber 19, the walls of the tubes 27 and the top of the base 11.

The next step is to lower the gas heating bell 32 into the position shown in Fig. 1 and energize the heating elements 34. When the temperature of the heating elements begins to rise, the convection blower 12 is started. The blades of the blower are so shaped that they force the gas within the heating chamber 17 laterally across the face of the base 11, up the passage 30 and into the first extremities 29 of the radiant heating tubes 27. From there, 60 the gas moves through the tubes 27, into the interior of the baffle chamber 17, through and around the work, and finally it passes through the aperture in the baffle plate 15 to the convection blower 12. As the temperature of the heating elements 34 rises, these elements radiate heat 65 and thus elevate the temperature of the radiant heating tubes 27. This heat is transferred to the gas as it passes through the tubes. The hot gas then transfers heat to the 70

work 36 as it passes around the work and thereby effects the annealing of the work.

The concentric square configuration of the tube exits permits the tubes to project uniformly spaced jets of heated gas into the chamber and as a result each jet supplies the same volume of heated gas to the chamber. As the heated gas advances toward the work, each portion of each cross-sectional area of the heating chamber is maintained at the same even heat. With the present arrangement of jets, uniform gas distribution is attained throughout the interior of the baffle chamber 19 and as a consequence there is uniform annealing of the work.

The temperature to which the gas is elevated and the length of time for which the work remains within the furnace are, of course, dependent upon the nature of the work. When the proper time has elapsed, the heating bell 32 and then the heating chamber 17 are raised and the work permitted to cool.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. A heat treating furnace comprising a base, means for supporting work pieces above said base, a heating chamber adapted to cooperate with said base to form a gas tight enclosure, a baffle chamber concentrically secured within said heating chamber to form a gas passage therebetween, a plurality of return bend tubes secured to one end of the heating chamber and interconnecting said baffle chamber and said passage, means for forcing circulation of a gas through said passage, said tubes, and said baffle chamber, and means for heating the gas circulating through the tubes.

2. A heat treating furnace comprising a base, means for supporting work pieces above said base, a double walled heating chamber having a perforated end supporting said walls in concentric relationship and adapted to surround said supporting means when resting on said base, means on the exterior wall of said chamber and on said base for forming a gas tight seal therebetween, a plurality of return bend tubes positioned in the perforations in the end of said chamber and interconnecting the interior of said chamber and the passage formed between the double walls of said chamber, means for forcing circulation of a gas through said passage and said tubes and into contact with work pieces supported within the interior of said chamber, and means for heating the gas circulating through said tubes.

3. A heat treating furnace comprising a base, an open grillwork for supporting work pieces above said base, a bell-shaped heating chamber adapted to surround said grillwork when resting on said base, means on said chamber and said base for forming a gas tight seal therebetween, a baffle depending from the end of said chamber toward the open end thereof, said baffle being adapted to fit closely around said supporting grillwork and terminating in an open end spaced inwardly from the plane of the open end of said chamber, a plurality of return bend tubes positioned in apertures in the closed end of said chamber for interconnecting the interior of said baffle and the passage formed between the walls of said baffle and the walls of said chamber, a convection blower for circulating a gas through said passage, said tubes, and said baffle, and a heater adapted to surround said tubes when resting on said base for heating the gas circulating through the tubes.

4. A heat treating furnace comprising a base, an apertured baffle plate fixed in spaced relationship above said base, an open grillwork for supporting work pieces fixed in spaced relationship above said baffle plate, a bell-shaped heating chamber having a plurality of apertures formed in the closed end thereof and adapted to enclose

said grillwork when resting on said base, means on said heating chamber and said base for forming a gas tight seal therebetween, a baffle chamber concentrically secured within said heating chamber and forming a gas passage

5 therebetween, said baffle chamber being adapted to fit closely about said grillwork and spaced away from the base when the heating chamber is resting on said base, a plurality of return bend tubes positioned in said apertures in the closed end of said heating chamber for connecting the gas passage with the interior of the baffle chamber, a convection blower secured to the underside of said base with the blades thereof interposed between said base and said baffle plate for forcing circulation of a gas throughout the circuit defined by the gas passage, 10 the tubes, the interior of said baffle chamber, and the space between the baffle plate and base, a bell-shaped housing adapted to surround said tubes when resting on the closed end of said heating chamber, and a plurality of heating elements secured within said housing for 15 radiantly heating said tubes to elevate the temperature of the gas circulating therethrough.

5. A heat treating furnace comprising a base, means for supporting work pieces above said base, a heating chamber adapted to cooperate with said base to form a gas tight enclosure, 20 a baffle chamber concentrically secured within said heating chamber to form a gas passage therebetween, a first group of return bend tubes secured to the closed end of said heating chamber extending from apertures opening on the space between the walls of the 25 heating and baffle chambers and terminating in exit apertures that are equally spaced to define a square pattern within the confines of the baffle chamber, a second group of return bend tubes extending from additional apertures opening on the space between the walls of the heating and baffle chambers and terminating in exit apertures that are 30 equally spaced to define a second square pattern within said first square pattern and spaced therefrom a distance substantially equal to the distance between any two adjacent exit apertures in said first and second pattern, 35 means for forcing circulation of a gas through said passage, said tubes, and said baffle chamber, and means for heating the gas circulating through the tubes.

6. A heat treating furnace comprising a base, an apertured baffle plate fixed in spaced relationship above said base, an open grillwork for supporting work pieces fixed in spaced relationship above said baffle plate, a bell-shaped heating chamber having a plurality of apertures formed in the closed end thereof and adapted to enclose said grillwork when resting on said base, means on said heating chamber and said base for forming a gas tight seal therebetween, a baffle chamber concentrically secured within said heating chamber and forming a gas passage therebetween, said baffle chamber being adapted to fit closely about said grillwork and spaced away from the base when the heating chamber is resting on the base, a first group of return bend tubes secured to the closed end of said heating chamber extending from the apertures opening on the space between the walls of the heating and baffle chambers and terminating in exit apertures that are 45 equally spaced to define a square pattern within the confines of the baffle chamber, a second group of return bend tubes extending from additional apertures opening on the space between the walls of the heating and baffle chambers and terminating in exit apertures that are 50 equally spaced to define a second square pattern within said first square pattern and spaced therefrom a distance substantially equal to the distance between any two adjacent exit apertures in said first and second pattern, a 55 convection blower secured to the underside of said base with the blades thereof interposed between said base and said baffle plate for forcing circulation of a gas throughout the circuit defined by the gas passage, the tubes, the interior of the baffle chamber, and the space between the baffle plate and base, a bell-shaped housing adapted to 60 65 70 75

surround said tubes when resting on the closed end of said heating chamber, and a plurality of heating elements secured within said housing for radiantly heating said tubes to elevate the temperature of the gas circulating therethrough.
